RADIO-GUIDING SYSTEM

Charles Aribert, Paris, France, assignor to Societe
française Sadir-Carpentier, Paris, France, a
corporation of France

Application January 12, 1949, Serial No. 70,481
In France January 15, 1948

3 Claims. (Cl. 343—107)

1

My invention relates to a radio-aligning system providing four alignment axes.

It is known that radio fields varying in percentage modulation have with reference to radio fields varying in field strength, general advantages that are derived from the fact that the carrier waves have an amplitude that is substantially independent of azimuth, whereby certain objectionable effects that are produced through the operation of the anti-fading system of the receiver system, are removed.

The arrangement according to my invention is characterized by the use of four aerials, for instance four vertical dipoles or doublet antennas located at the apices of a square. The antennas located at the ends of each diagonal line of said square are fed by current of the same frequency, phase and amplitude and are similarly modulated. Furthermore only the side bands are transmitted. Each of these pairs of aerials is fed in phase opposition with reference to the other pair. Lastly a central aerial transmits a partly modulated wave having the same high frequency as the preceding aerials. This partly modulated wave is substantially in phase with that transmitted by one of the diagonal pair of aerials, the phase of the partial modulation being reversed as in the case of conventional radio-aligning means at a predetermined rhythm, for instance dot-dash rhythm or the complementary rhythm, generally known as the *a—n* rhythm.

In accompanying drawings illustrating my invention by way of example in an entirely dia-grammatic manner:

Fig. 1 shows the location of the aerials,

Fig. 2 illustrates the means for feeding the aerials.

Fig. 3 illustrates a modification in the arrangement of the aerials.

As shown in Fig. 1 the aerials 1, 2, 3 and 4 are located at the apices of a polygon. As disclosed hereinabove, the aerials 1 and 3 are fed with currents of identical phases and the value of which is

$$I_1 = I \sin wt \sin pt$$

The high frequency wave transmitted has a frequency w and the modulation has a frequency p . It is apparent that only the side bands are transmitted. Similarly the aerials 2 and 4 are fed with identical currents having the value $I_2 = -I \sin wt \sin pt$. It is apparent that the currents I_1 — I_2 are identical and differ only through their sign.

Lastly the central aerial 5 is fed with a current

2

$$I_3 = I \sin wt (1 \pm K \sin pt)$$

the signs + and — being substituted for one another at the desired rhythm, say a dot and dash rhythm.

5 It is apparent that the current in the central aerial has the same frequency and phase as concerns its high frequency component and also, except for its sign, as concerns its modulating component as the current fed to the aerials at the four apices of the square.

Calculation shows readily that the component field of the aerials 1—2—3—4 in a direction forming an angle θ with the diagonal line 1—3 is approximately equal except for a multiplying factor depending on distance, conditions of propagation, etc. to

$$H_s = \sin wt \sin pt \cos 2\theta$$

20 This relationship holds true, provided the diagonal of the square defined by the aerials may have a length that is less than or at the most equal to the wavelength of the high frequency transmitted. Through addition of said field to 25 that produced by the omni-directional central aerial 5, there is obtained a total field the value of which is, except for a constant multiplying factor, equal to:

$$H = \sin wt [1 + \sin pt (k_2 \cos 2\theta \mp k_3)] \quad (1)$$

This leads to a value of the percentage of modulation that is equal to

$$r = k_2 \cos 2\theta \mp k_3 \quad (2)$$

It is thus apparent that the percentage of modulation of the field received along the direction θ does not vary or more accurately it merely changes in sign without changing in absolute value when

$$\cos 2\theta = 0$$

which means

$$45 \quad \theta = \frac{\pi}{4} \text{ and } \theta = \frac{3\pi}{4}$$

It is thus apparent that the four half axes assume directions that are parallel with the sides of the aerial square 1—2—3—4.

50 It is well known that the reception of such a field may be performed through a conventional receiver, say a receiver of the type used for broadcasting if the modulation is at audio frequency or else any other receiver that is well known per se, such receivers obviously not form-

ing part of the present invention that covers only the production of the radio aligning means.

According to a modification, the reversal in phase, instead of affecting the modulated portion of the waves transmitted by the central aerial is performed on the feed of the two diagonal pairs of aerials. It is immediately apparent that in this modification the coefficient k_3 of the relationship (1) retains the same sign while the coefficient k_2 of the same equation changes sign at each reversal: the Equation 2 is modified by way of consequence while the results obtained remain the same.

Fig. 2 illustrates a manner of feeding the five aerials assumed to be in the present case dipole antennas, to wit the dipoles 1—2—3—4 arranged at the apices of the square and a central dipole antenna 5. The dipole antennas 1—3 are fed directly in parallel through the feeders 18 and 19 starting from a central feeder 6. On the other hand the dipole antennas 2 and 6 are fed similarly by the feeders 20—21 fed in their turn by the same primary feeder 6 but with a crossing of the wires forming the feeders 20 and 21 which provides the desired phase opposition; the different feeders are adjusted so as to produce currents of equal amplitude in the four dipole antennas. As to the central aerial 5, it is fed through a separate feeder 7.

An oscillator 9, the frequency of which is w , feeds high frequency current to both transmitters 9 and 10 that are fed on the other hand by the oscillator 11 with the modulating voltage having a frequency p .

As disclosed hereinabove the transmitter 9 produces a single side band with suppression of the carrier wave whereas the transmitter 10 produces a wave that is partly modulated. The transmitter 10 includes furthermore means 22 for reversing the phase of the modulation at the desired rhythm.

In the modification disclosed hereinabove, said phase reversing means are incorporated to the transmitter 9.

Fig. 3 illustrates a further embodiment of the aerials; the transmitters 9 and 10 and oscillators 8 and 11 perform the same functions in this embodiment as hereinabove and provide the same currents. The aerial 5 is fed in the same manner through the feeder 7 starting from the transmitter 10; only the manner of feeding the aerials 1—2—3—4 is changed. The feeder 6 is subdivided and forms two feeders 12—13 that are fed in parallel. Each of these secondary feeders 12—13 forms again two branches as shown, comprising the terminal feeders 14 and 15 on one hand and 16 and 17 on the other. The leads of the feeders 17 and 15 are crossed with reference to those of the feeders 14 and 16. Furthermore, the leads of feeder 13 are crossed with reference to those of feeder 12. Obviously this arrangement provides the same result, to wit, a feed in parallel of the dipole antennas 1—3 and of the dipole antennas 2—4, the system of antennas 1—3 being fed in phase opposition with reference to the system of antennas 2—4.

Obviously many details may be modified in the arrangement disclosed without widening unduly thereby the scope of the invention as defined in accompanying claims.

What I claim is:

1. Radio transmitting apparatus comprising four aerials positioned at the apices of a four sided polygon, radio apparatus for feeding the pair of aerials positioned at the ends of one di-

agonal of said polygon with high frequency oscillations of predetermined amplitude, the wave length of said oscillations being on the order of the length of the longer diagonal of said polygon, apparatus for feeding high frequency oscillations of the same amplitude and same high frequency as said first mentioned oscillations to the other pair of aerials located at the ends of the other diagonal of said polygon, said oscillations fed to said last mentioned pair of aerials being of opposite phase from that of said oscillations fed to said first mentioned pair of aerials, an additional aerial located substantially at the center of said polygon, modulating apparatus for modulating the oscillations supplied to said four aerials at the same frequency, phase and amplitude, apparatus for feeding high frequency oscillations of the same frequency and phase of said first mentioned oscillations to said additional aerial, modulating apparatus for modulating the oscillations fed to said additional aerial, apparatus for periodically reversing the relative phase of said last mentioned modulating apparatus with reference to the phase of the modulations applied to the oscillations fed to said first mentioned pair of aerials to provide alternately phase coincidence and phase concordance between the phases of these last two modulations.

2. Radio transmitting apparatus comprising four aerials positioned at the apices of a four sided polygon, radio apparatus for feeding the pair of aerials positioned at the ends of one diagonal of said polygon with high frequency oscillations of predetermined amplitude, the wave length of said oscillations being on the order of the length of the longer diagonal of said polygon, apparatus for feeding high frequency oscillations of the same amplitude and same high frequency as said first mentioned oscillations to the other pair of aerials located at the ends of the other diagonal of said polygon, said oscillations fed to said last mentioned pair of aerials being of opposite phase from that of said oscillations fed to said first mentioned pair of aerials, an additional aerial located substantially at the center of said polygon, modulating apparatus for modulating the oscillations supplied to said four aerials at the same frequency, phase and amplitude, apparatus for feeding high frequency oscillations of the same frequency and phase of said first mentioned oscillations to said additional aerial, modulating apparatus for partially modulating the oscillations fed to said additional aerial, and apparatus for reversing the phase of the currents fed to said additional antenna in accordance with a predetermined pattern.

3. Radio transmitting apparatus comprising four aerials positioned at the apices of a four sided polygon, radio apparatus for feeding the pair of aerials positioned at the ends of one diagonal of said polygon with high frequency oscillations of predetermined amplitude, the wave length of said oscillations being of the order of the length of the longer diagonal of said polygon, apparatus for feeding high frequency oscillations of the same amplitude and same high frequency as said first mentioned oscillations to the other pair of aerials located at the ends of the other diagonal of said polygon, said oscillations fed to said last mentioned pair of aerials being of opposite phase from that of said oscillations fed to said first mentioned pair of aerials, an additional aerial located substantially at the center of said polygon, modulating apparatus for modulating the

oscillations supplied to said four aerials at the same frequency, phase and amplitude, apparatus for feeding high frequency oscillations of the same frequency and phase of said first mentioned oscillations to said additional aerial, modulating apparatus for modulating the oscillations fed to said additional aerial, and apparatus for periodically reversing the phase of the currents fed to said first mentioned antennas in accordance with a predetermined pattern.
